MACHINE FOR TAKING FINGERPRINTS

Theodore H. Krueger, Stratford, Conn., assignor
to Better Packages, Inc., a corporation of New
York

Application November 15, 1952, Serial No. 22,309

Term of patent 14 years

(Cl. D64—11)

To all whom it may concern:

Be it known that I, Theodore H. Krueger, a citizen of the United States, residing in Stratford, county of Fairfield, State of Connecticut, have invented a new, original, and ornamental Design for a Machine for Taking Fingerprints, of which the following is a specification, reference being had to the accompanying drawing, forming part thereof, in which

Figure 1 is a plan view of a machine for taking fingerprints, embodying my new design;

Figure 2 is a front elevation of the machine;
Figure 3 is an end elevation of the machine;
and

Figure 4 is a rear perspective view of the machine.

I claim:

The ornamental design for a machine for taking fingerprints, substantially as shown.

THEODORE H. KRUEGER.
